ANODE AND CATHODE ARRANGEMENT FOR A NUMERAL DISPLAY

Abul Abbas Mesbahuddin Ahmed, Harrisburg, Pa.,
assignor to AMP Incorporated, Harrisburg, Pa.

Filed Dec. 12, 1973, Ser. No. 424,136

Term of patent 14 years

Int. Cl. D14—02

U.S. Cl. D26—5 C

The figure is a plan view of an anode and cathode arrangement for a numeral display showing my new design. It is understood that the unit shown may be repeated indefinitely. The anode and cathode arrangement has insubstantial thickness.

I claim:

The ornamental design for an anode and cathode arrangement for a numeral display, as shown and described.
